UNITED STATES PATENT OFFICE

2,585,131

CONTROLLING MEANS FOR FLUID-OPERATED MACHINES

Bernhardt Jorgensen, Marblehead, Mass., assignor to United Shoe Machinery Corporation, Flemington, N. J., a corporation of New Jersey

Application July 6, 1949, Serial No. 103,217

3 Claims. (Cl. 60—97)

1

This invention relates to fluid-operated machines, and more particularly to means for controlling the operation of such machines. The invention is herein shown as applied to a fluid-operated toe-lasting machine for use in the manufacture of shoes, constructed generally as disclosed in United States Letters Patent No. 2,324,509, granted on July 20, 1943 on an application of mine, but it will be understood that it is not limited to machines of that particular character.

The machine shown in the above-mentioned Letters Patent includes in its organization a plurality of fluid-operated mechanisms, valves for controlling the admission of operating fluid respectively to the different mechanisms from a pressure chamber in which the fluid, preferably light oil, is maintained under pressure by a pump, and controlling means rotatable in one direction to initiate the operations of the different mechanisms in predetermined time relation to one another by control of the valves. The controlling means is thus rotated by a piston movable in a cylinder to one end of which fluid is admitted from the pressure chamber and from which the fluid is thereafter released to stop the operation of the machine. Upon such release of the fluid the piston is moved reversely to its initial position, without reverse rotation of the controlling means, by a spring wound around the axis of the controlling means and subjected to stress by the operative movement of the piston. To control variably the speed of operation of the machine, this piston has rigidly connected thereto another piston movable in a second cylinder from one end of which it expels fluid past an adjustable needle valve when the machine is operating and into which it draws fluid by suction from a reservoir or sump when the first-mentioned piston is returned by the spring.

The present invention provides means whereby the reverse movement of the fluid-operated member which operates the rotatable valve-controlling means is effected also by fluid pressure, the above-mentioned spring being eliminated. To this end, the construction herein shown includes a pressure-controlled valve which, in response to the drop in the pressure of the fluid in the first above-mentioned cylinder when the fluid is released from that cylinder, admits fluid under pressure to the second cylinder to act on the piston therein and thereby to effect the reverse movement of the first-mentioned piston. When fluid under pressure is admitted to the first-mentioned cylinder to operate the rotatable valve-controlling means, the pressure-con-

2

trolled valve, in response to the pressure of the fluid thus admitted, moves into position to interrupt communication between the second cylinder and the source of fluid under pressure, the subsequent exhaust of the fluid from the second cylinder as the first-mentioned piston is operated being adjustably restricted to determine the speed of rotation of the valve-controlled means. To assist in avoiding the presence in the liquid fluid of any air such as might cause the valve-controlling means to run irregularly, a passageway is provided for exhaust of the fluid from the second cylinder into a chamber in open communication with the inactive ends of both cylinders; the chamber having an outlet for the fluid at such a height as to keep the chamber and the above passageway full of the fluid.

The novel features of the invention will now be more particularly described with reference to the accompanying drawings and thereafter pointed out in the claims.

In the drawings,

Fig. 1 is a view partly in left-hand side elevation and partly in section of a portion of the machine to which the invention is herein shown as applied;

Fig. 2 is a view of a portion of the machine in right-hand side elevation, with parts broken away;

Fig. 3 is mainly a section on the line III—III of Fig. 2; and

Fig. 4 is mainly a diagrammatic view illustrating the manner in which fluid pressure is utilized in the operation and control of the machine.

In view of the disclosure in the above-mentioned Letters Patent only as much of the machine to which the invention is herein shown as applied as it is necessary to refer to for an understanding of the invention will be herein described. The machine is provided with a plurality of fluid-operated mechanisms which are operated in predetermined time relation to one another in the course of a cycle of automatic operations of the machine. Portions of two of these mechanisms, each comprising a pair of cylinder-and-piston devices, are shown diagrammatically in Fig. 4 and are identified respectively by the reference characters 2 and 4. The several mechanisms are supplied with operating fluid at the appropriate times in the cycle of operations through automatically controlled valves 6 from a source of supply of fluid under pressure comprising a chamber 8 formed in a casting 10 secured to the lower face of a horizontal plate 12 which serves as a closure for the top of the chamber. Secured also to the

plate 12 is a casting 14 which provides a reservoir or sump 15 for fluid not under pressure, the casting 10 being located in the upper portion of the sump. A pump 16 (Fig. 4) driven continuously by an electric motor 18 draws fluid, preferably light oil, from the sump and delivers the fluid through a pipe 20 into the chamber 8. When the machine is not in operation the fluid is returned from the chamber 8 to the sump, without developing the required full operating pressure in the chamber, through a sleeve valve 22 constructed substantially as disclosed in the previously mentioned Letters Patent. Through mechanism not herein fully shown but constructed as also disclosed in said Letters Patent the valve 22 is operated prior to each cycle of operations of the machine by depression of a treadle 24 (Fig. 1) to close the outlet from the chamber 8 and thus to cause the development of the necessary pressure in the chamber, the pressure being limited by a spring-controlled relief valve 26 past which the excess fluid delivered by the pump flows through a bypass 28 back to the sump.

The cycle of operations corresponds to one complete revolution of a valve-controlling device which in the construction herein shown, in accordance more particularly with the disclosure of Letters Patent No. 2,367,782, granted on January 23, 1945 on an application of mine, comprises a drum 30 having thereon a plurality of fingers, some of which are shown at 32 in Fig. 4, for moving the valves 6 at the proper times to admit operating fluid to the several fluid-operated mechanisms and for thereafter releasing the valves to permit them to be returned by springs into positions to release the fluid from the mechanisms. The valves are located in the upper portion of the sump at opposite sides of the chamber 8, and the fluid thus released by the valves returns to the sump. Also carried by the drum is a finger 34 which at the end of the cycle causes the valve 22 to return to its initial position to release the fluid from the chamber 8.

The drum 30, in the construction herein shown, is provided at one end with a shaft 36 (Fig. 3) rotatable in a bearing formed in a bracket 38 which is mounted on the plate 12, and at the other end with a shaft 40 rotatable in a casting 42 on the plate 12 and in a bearing member 44 secured to this casting. The drum is turned in the direction of the arrow α (Fig. 1) by a fluid-operated piston 46 (Fig. 2) mounted in a cylinder 48 secured to the casting 42. To turn the drum in that direction there is provided a one-way clutch 50 which in the construction herein shown is a Horton clutch comprising a member 52 keyed to the shaft 40 and an annular member 54 encircling the member 52. Mounted in recesses in the member 52 are rolls 56 controlled by springs 58 and serving to couple the member 54 to the member 52 when the member 54 is turned in the direction of the arrow α but to permit the member 54 to turn freely in the reverse direction on the member 52. To insure that the drum 30 will not be turned in the reverse direction there is mounted on the shaft 36 (Fig. 3) a spring 60 which is under compression between a washer 62 confined by a nut 64 on the end of the shaft and another washer 66 in frictional engagement with a flat face of the bracket 38. The annular clutch member 54 has on its periphery a series of gear teeth 68 in engagement with teeth 70 formed on a piston rod 72 to one end of which the piston 46

is secured, the piston rod in the construction herein shown being located below the clutch.

Fluid is admitted to the cylinder 48 to operate the piston 46 and is thereafter exhausted or released therefrom through a pipe 74 communicating with the outer end of the cylinder, the admission and exhaust of the fluid being controlled by a valve 76 (Fig. 1). As disclosed in Letters Patent No. 2,324,509, this valve is a sleeve valve 10 slidingly mounted on a tube 78 which is confined between the casting 10 and a member 80 provided with a passageway 82 in communication with the pipe 74. One end of the tube 78 is in communication with the chamber 8 and the other end with the passageway 82, and between its ends the tube is divided by a partition 84. Extending through the tube at one side of this partition are ports 86 and at the other side of the partition ports 88. The valve 76 has therein an annular recess 90 through which the ports 86 and 88 may communicate with one another to supply fluid from the chamber 8 to the cylinder 48. Initially, however, as shown in Fig. 1, the valve is positioned against the casting 10 with the ports 88 uncovered and open to the sump. Movement of the valve toward the right with reference to Fig. 1 to admit fluid to the cylinder 48 is effected by swinging movement of an arm 92 the lower end of which is connected to the valve and the upper end of 25 which is pivotally mounted on a pin 94 supported on a bracket 96 on the plate 12. A spring 98 connected to the arm 92 holds the valve initially against the casting 10. Also pivotally mounted on the pin 94 is a two-part lever 100 by movement of which in a counterclockwise direction with reference to Fig. 1 the arm 92 is swung against the resistance of the spring 98, the lever thus acting on the arm through a spring 99. The two parts of the lever 100 are pivotally connected 30 together by a pin 102 but are held normally in a fixed relation to each other by a spring 104 connected to pins on the two parts, the relation of the two parts to each other being determined by engagement of a lug on one part with a shoulder 35 106 on the other part. Also pivotally mounted on the pin 102 is a latch member 108 which is normally held by a spring 110 in engagement with a vertical face on the bracket 96 and is swung by the spring into a notch 112 in the bracket when the lever 100 is swung in the direction to operate the valve 76. By this latch, therefore, the valve is retained in position to admit the fluid to the cylinder 48. The latch is swung in a clockwise direction to release the lever 100 and thus to permit the valve 76 to be returned to its initial position by the spring 98 by means of a lever 114 which is pivotally mounted on the pin 94 and one arm of which bears upwardly against a shoulder on the latch, the arm being held against 40 this shoulder by a light spring 116 connected to the lever 114. The lever 114 is thus operated at the proper time to stop the machine at the end of the cycle by the engagement of a finger 118 on the drum 30 therewith, the finger passing beyond the lever prior to the completion of the cycle, as shown in Fig. 1. Another finger 120 (Figs. 1 and 4) on the drum acts on the lever 114 to stop the machine before the end of the cycle, for a purpose explained in Letters Patent No. 2,324,509, after which, as further described in said Letters Patent, the valve 76 is operated automatically to cause the machine to complete the cycle.

It will be understood that movement of the valve 76 to admit fluid to the cylinder 48 and thus

to start the rotation of the drum 30 is effected by upward movement of the front end of the lever 100, this being the end of the lever which is at the right in Fig. 1. For thus operating the lever there is pivotally connected to a pin 122 on its front end a yoke member 124 in which is slidingly mounted the reduced upper end portion of a rod 126. This portion of the rod extends upwardly through the lower end of the yoke and through a transverse wall 128 on the yoke, and between this wall and a collar 130 fast on the rod is a compression spring 132. Through this spring, therefore, upward movement is imparted yieldingly by the rod to the yoke. At its lower end the rod 126 is connected to one arm of a bell-crank lever 134 which is mounted to swing about a pin 136 supported on a bracket 138 at the base of the machine. The mechanism for operating this bell-crank lever to impart the upward movement to the rod 126 is not herein completely shown, since the construction is the same as disclosed in Letters Patent No. 2,324,509. Such movement of the rod to start the cycle of operations is effected by a second depression of the treadle 24 after the treadle has been first depressed to cause the valve 22 to close the outlet from the chamber 8 as hereinbefore described. As further disclosed in the last-mentioned Letters Patent, a latch 140 is arranged to engage the pin 122 to prevent movement of the lever 100 until near the end of the upward movement of the rod 126, whereupon the latch is swung to release the pin and to permit the spring 132, compressed by the upward movement of the rod, to move the valve 76 quickly into position to admit the fluid to the cylinder 48.

Whenever the valve 76 is returned in the manner above described into position to release the fluid from the cylinder 48, whether at the end of the cycle or prior to the end of the cycle, the piston 46 is immediately returned to its initial position. For this purpose, in the construction herein shown, a cylinder 142 is secured to the casting 42 at the opposite side of the casting from the cylinder 48 and in alinement with the latter cylinder. Mounted in the cylinder 142 is a piston 144 fast on the opposite end of the piston rod 72 from the piston 46. Mounted in a block 146 fast on the upper end of the casting 42 is a vertically movable piston valve 148 held normally in upraised position by a spring 150 which is mounted in a recess in the valve and is seated at its lower end on a plate 152. The valve is provided with an annular recess 154, and when it is in its normal upraised position, as shown, this annular recess is in communication, through a passageway 156 in the block 146, with a pipe 158 leading to the outer end of the cylinder 142. Also in communication with the annular recess in the valve is a passageway 160 in the block 146, this passageway being connected by a pipe 162 with the chamber 8. Initially, therefore, the cylinder 142 is in communication with the chamber 8 through the pipe 158, the annular recess 154 in the valve 148 and the pipe 162 and contains fluid under the same pressure as that in the chamber

8. Leading from the cylinder 48 to a port 164 in the upper end of the block 146 is a pipe 166, the port 164 communicating with an annular recess 168 in the block around the upper end of the valve 148 when the valve is in its uppermost position. When the valve 76, therefore, is moved into position to admit fluid under pressure from the chamber 8 to the cylinder 48 the same pressure is established through the pipe 166 in the

annular recess 168 and forces the valve 148 downwardly against the resistance of the spring 150, the valve engaging the plate 152 to limit its downward movement. This downward movement of the valve closes the passageway 156 and thus interrupts communication between the chamber 8 and the cylinder 142. Extending downwardly in the block 146 from the passageway 156 is another passageway 170 in communication at its lower end with a chamber 172 in the casting 42, this being a chamber in which the clutch 50 is located and which is in open communication with the inner ends of the cylinders 48 and 142. Adjustably threaded in the block 146 is a needle valve 174 which partially closes the passageway 170 but permits restricted flow of the fluid from the passageway 156 to the chamber 172. Accordingly, when the piston 46 is operated by the fluid admitted to the cylinder 48 fluid is forced out of the cylinder 142 by the piston 144, this fluid flowing through the pipe 158 and through the restricted passage 170 into the chamber 172. Leading from the upper portion of this chamber is a pipe 176 for conducting fluid from this chamber back to the sump. This pipe, as shown, extends first upwardly and then downwardly to form a loop high enough to insure that the chamber 172 and the passageways 156 and 170 in the block 146 will be at all times full of fluid. This is a safeguard against entrapment of air in the liquid fluid, as is also the fact that such fluid from the chamber 172 always fills any space in the cylinders 48 and 142 at the inner ends of the pistons 46 and 144. It will be understood that the needle valve 174 restricts, as determined by its adjustment, the flow of the fluid from the cylinder 142 when the piston 46 is operated and thereby determines the speed at which the drum 30 is rotated. It will further be understood that when the piston 46 and the valve 148 are in their initial positions a small quantity of the fluid conducted by the pipe 162 from the chamber 8 to the passageway 160 and the annular recess 154 in the valve will escape past the needle valve 174 to the chamber 172 and thence to the sump. This affords further insurance that the chamber 172 will be kept full of the fluid.

When the valve 76 is moved reversely into position to release the fluid from the cylinder 48 the drop in the pressure above the valve 148 causes the valve to be returned to its initial position by the spring 150. In this manner communication is again established through the pipes 162 and 158 between the chamber 8 and the cylinder 142, so that the fluid under pressure is forced into this cylinder to act on the piston 144 and thereby to return the piston 46 to its initial position. In this operation, as hereinbefore explained, the annular clutch member 54 turns idly about the member 52, the drum 30 remaining in the position to which it was previously moved. Since the flow of the fluid from the chamber 8 to the cylinder 142 and the flow of the fluid from the cylinder 48 back to the sump are unrestricted, the piston 46 is returned very quickly to its initial position.

It will be evident that when the drum 30 comes to a stop at the end of the cycle the valve 22 will have been moved into position to release the fluid from the chamber 8. In the construction herein shown, therefore, the outlet controlled by this valve is sufficiently restricted as compared with the capacity of the pump 16 to insure that enough pressure will still be maintained in the chamber 75 8 to return the piston 46 at that time, only a

small amount of pressure being required for that purpose. The provision thus afforded for a small amount of pressure in the chamber 8 when the pump is operating and the valve 22 is in open position, and the fact that the cylinder 142 is normally in communication with the chamber 8, assist in insuring that even though there may be a substantial interval between successive cycles of operations of the machine the cylinder 142 will be completely filled with fluid when the machine is started, thus avoiding the possibility of any sudden abnormally rapid movement of the piston 46 and the drum 30 upon admission of the fluid to the cylinder 48.

Having described the invention, what I claim as new and desire to secure by Letters Patent of the United States is:

1. In a fluid-operated machine, a plurality of fluid-operated mechanisms, valves for controlling the admission of fluid respectively to said different mechanisms, controlling means rotatable in one direction to initiate the operations of the different mechanisms in predetermined time relation to one another by control of said valves, a source of liquid fluid under pressure, a member having a chamber therein, a cylinder arranged to extend outwardly from said member and having therein a piston movable thus to rotate said controlling means, said cylinder being open at its inner end to said chamber, valve means for admitting fluid from said source to the outer end of said cylinder to operate said piston and for thereafter releasing the fluid therefrom, another cylinder arranged to extend outwardly from said member in the opposite direction from said first-named cylinder and having therein a piston connected to said first-named piston to move in unison therewith, said other cylinder also being open at its inner end to said chamber, a valve responsive to the drop in the pressure of the fluid in the first-named cylinder when the fluid is released therefrom for admitting fluid from said source to the outer end of said other cylinder to return said first-named piston, means providing a passageway for exhaust of fluid from said other cylinder to said chamber when the first-named piston is operated, and means providing an outlet for the fluid from said chamber at such a height as to keep the chamber and said passageway full of the fluid.

2. In a fluid-operated machine, a plurality of fluid-operated mechanisms, valves for controlling the admission of fluid respectively to said different mechanisms, controlling means rotatable in one direction to initiate the operations of the different mechanisms in predetermined time relation to one another by control of said valves, a source of liquid fluid under pressure, a member having a chamber therein, a cylinder arranged to extend outwardly from said member and having therein a piston movable thus to rotate said controlling means, said cylinder being open at its inner end to said chamber, valve means for admitting fluid from said source to the outer end of said cylinder to operate said piston and for thereafter releasing the fluid therefrom, another cylinder arranged to extend outwardly from said member in the opposite direction from said first-named cylinder and having therein a piston connected to said first-named piston to move in

unison therewith, said other cylinder also being open at its inner end to said chamber and being initially in communication at its outer end with said source to maintain the first-named piston in initial position, a valve controlled by the pressure of the fluid admitted to said first-named cylinder and movable by such pressure to interrupt communication between said source and said other cylinder, means providing a passageway for exhaust of fluid from said other cylinder to said chamber when the fluid is admitted to the first-named cylinder, and means providing an outlet for the fluid from said chamber at such a height as to keep the chamber and said passageway full of the fluid.

3. In a fluid-operated machine, a plurality of fluid-operated mechanisms, valves for controlling the admission of fluid respectively to said different mechanisms, controlling means rotatable in one direction to initiate the operations of the different mechanisms in predetermined time relation to one another by control of said valves, a source of liquid fluid under pressure, a member having a chamber therein, a cylinder arranged to extend outwardly from said member and having therein a piston movable thus to rotate said controlling means, said cylinder being open at its inner end to said chamber, valve means for admitting fluid from said source to the outer end of said cylinder to operate said piston and for thereafter releasing the fluid therefrom, another cylinder arranged to extend outwardly from said member in the opposite direction from said first-named cylinder and having therein a piston connected to said first-named piston to move in unison therewith, said other cylinder also being open at its inner end to said chamber and being initially in communication at its outer end with said source to maintain the first-named piston in initial position, a valve controlled by the pressure of the fluid admitted to said first-named cylinder and movable by such pressure to interrupt communication between said source and said other cylinder, means providing a passageway for exhaust of fluid from said other cylinder to said chamber when the fluid is admitted to the first-named cylinder, and means providing an outlet for the fluid from said chamber at such a height as to keep the chamber and said passageway full of the fluid, said passageway being arranged to permit flow of fluid from said source to said chamber and thence through said outlet when the first-named piston is in its initial position.
